(57) **CLAIM**

The ornamental design for a portable computer, as shown and described.

DESCRIPTION

FIG. 1 is a top front perspective view of a portable computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is another right side view thereof, with a display portion of the portable computer being obliquely positioned at a rear of the portable computer; and,

FIG. 10 is another top front perspective view thereof, wherein the display portion of the portable computer is positioned to be closed on a keyboard body of the portable computer.

The broken lines illustrating portions of the portable computer are for environmental purposes only and form no part of the claimed design.
